UNITED STATES PATENT OFFICE.

FRANKLIN LAWRENCE, OF PHILADELPHIA, PENNSYLVANIA.

IMPROVEMENT IN BLAST AND CUPOLA FURNACES.

Specification forming part of Letters Patent No. **142,482**, dated September 2, 1873; application filed July 2, 1873.

To all whom it may concern:

Be it known that I, FRANKLIN LAWRENCE, of Philadelphia, Pennsylvania, have invented an Improved Cupola or Furnace, of which the following is a specification:

My invention relates to a mode of increasing the reducing effect of fuel in a cupola or furnace; and consists of improved devices whereby the upper portion of the furnace may be obstructed, so as to reduce the opening for the escape of the products of combustion to about the area of the blast-openings.

The devices which I employ are illustrated in the accompanying drawing, which represents a vertical section of the upper portion of a furnace or cupola, in which is suspended a disk, A.

The diameter of the disk A is such, compared with that of the interior of the upper portion or chimney B of the furnace, that the annular space between the two is about equal in area to that of the blast-pipes. When the furnace has to be fed, however, it is necessary that this disk should be elevated above the feed-hole a, and should occupy such a position as to present the least possible obstruction to the volumes of smoke and gases which emanate from the fuel; hence, the disk is suspended to a rod passing through a guide, e, fixed in the chimney, the rod being attached

to a chain passing over pulleys to any suitable raising and lowering mechanism. On raising the disk from the position shown by dotted lines its flange will catch the outer end of an arm, m, hung to the inside of the chimney, and on continuing to elevate the disk the arm will be gradually raised to a horizontal position, and the disk will gradually assume the vertical position shown, so as to present the least obstruction to the escaping products of combustion.

After charging, the disk may be lowered, as indicated by dotted lines, and retained in a horizontal position at the desired height, the arm falling with the disk.

I claim as my invention—

1. The disk A, arranged in a furnace, and adjustable, so as to be secured in either a horizontal or a vertical position, as specified.
2. The combination of the flanged disk A and its guided rod f with the arm m hung to the interior of the chimney, all substantially as set forth.

In testimony whereof I have signed my name to this specification in the presence of two subscribing witnesses.

FRANKLIN LAWRENCE.
